DESIGN FOR A COMBINATION MERCHANT- DISE DISPLAY RACK AND CABINET

Samuel D. Heed, Cincinnati, Ohio, assignor to The Gibson Art Company, Cincinnati, Ohio, a corporation of Ohio

Application January 19, 1937, Serial No. 67,158

Term of patent 14 years

To all whom it may concern:

Be it known that I, Samuel D. Heed, a citizen of the United States, residing in Cincinnati, in the county of Hamilton and State of Ohio, have invented a new, original, and ornamental Design for a Combination Merchandise Display Rack and Cabinet, of which the following is a specification, reference being had to the accompanying drawing, forming part thereof.

In the drawing:—

Fig. 1 is a perspective view taken from the front of the combination merchandise display rack and cabinet showing my design.

Fig. 2 is a perspective view taken from the rear of Fig. 1.

I claim:—

The ornamental design for a combination merchandise display rack and cabinet as shown.

SAMUEL D. HEED.
